PISTOL GRIP OR SIMILAR ARTICLE

Allan F. Barney, Box 49797, Los Angeles, Calif.

Filed Jan. 18, 1963, Ser. No. 73,234

Term of patent 14 years

(Cl. D30—1)

FIGURE 1 is a right side perspective view of a pistol grip showing my new design; its position when mounted on a pistol is indicated by the phantom line illustration of a pistol, which latter is for illustrative purposes only;

FIGURE 2 is a left side perspective view thereof;

FIGURES 3 and 4 are right and left elevational views showing the right and left sides, respectively, of the pistol grip;

FIGURE 5 is a rear view of the pistol grip;

FIGURE 6 is a front view of the pistol grip;

FIGURE 7 is a top plan view of the top end of the pistol grip including the thumb rest; and

FIGURE 8 is a bottom plan view of the bottom end of the pistol grip.

I claim:

The ornamental design for a pistol grip or similar article, as shown and described.
